[57] CLAIM

I claim the ornamental design for a set of glass inset panels for a front door and matching sidelight windows, as shown and described.

DESCRIPTION

FIG. 1 is a front view of a set of glass inset panels for a front door and matching sidelight windows showing my new design, it being understood the rear is a mirror image thereof.

FIG. 2 is a front view of a set of glass inset panels for a front door and matching sidelight windows showing a second embodiment of my new design, it being understood the rear is a mirror image thereof; and,

FIG. 3 is a front view of a set of glass inset panels for a front door and matching sidelight windows showing a third embodiment of my new design, it being understood the rear is a mirror image thereof.

The top, bottom, and side edges of the set of glass inset panels for a front door and matching sidelight windows form no part of the claimed design.
